Inventor:

Frank J. Cook

Cost B. Mueller.

UNITED STATES PATENT OFFICE.

FRANK J. COOK, OF CLEVELAND, OHIO, ASSIGNEE, BY MESNE ASSIGNMENTS, OF ONE-HALF TO JAMES E. DOYLE AND ONE-HALF TO CHARLES S. BRITTON, BOTH OF CLEVELAND, OHIO.

ELECTRICAL ELEMENT.

1,174,548.

Specification of Letters Patent.

Patented Mar. 7, 1916.

Application filed March 25, 1914. Serial No. 827,101.

To all whom it may concern:

Be it known that I, FRANK J. COOK, a citizen of the United States, residing at Cleveland, in the county of Cuyahoga and State of Ohio, have invented a new and useful Improvement in Electrical Elements, of which the following is a specification, the principle of the invention being herein explained and the best mode in which I have 10 contemplated applying that principle, so as to distinguish it from other inventions.

This invention relates to an electrical element and more particularly to a heating unit of an electrical character.

15 The object is the provision of an element which not only conserves, and hence intensifies the radiation of heat from itself, but which is especially adapted to concentrate the radiation of its heat in a given direction.

20 An incidental object is the attainment of a construction which will be sufficiently simple and economical of manufacture.

The inventive conception is embodied in 25 means which are hereinafter explained and variously combined in the claims, while the annexed drawing and particular description thereof together set forth in detail two certain means constituting my invention, the 30 disclosed means, however, being but some of various mechanical forms in which the principle of my invention may be applied.

Referring next to the drawing: Figure 35 I represents a plan of one form of my invention. Fig. II is an enlarged section of Fig. I. Fig. III is a perspective view of a modified form of my invention. Fig. IV is an enlarged section of the same.

With reference first to Figs. I and II 40 which illustrate the type of my invention which I regard as suitable for heating the inking-disk of a Gordon type of printing press, it will be noted that the construction involves a circular shaped compartment 1, 45 preferably of metal, and of U-shaped cross section, and a second compartment 2 of identical shape though very slightly larger, such that it may be adapted to effect a telescopic connection with the compartment 1 as 50 clearly seen in Fig. II. Disposed upon the bottom of the inner compartment is an asbestos lining 3, and similarly disposed against the opposed inner sides of the compartment 1 are a pair of asbestos linings 4 and 5 respectively. Resting upon the lining

3 and located equal distances from the linings 4 and 5 respectively are a pair of spacer rings 6 and 7 which are likewise preferably of asbestos composition. Extending between and resting against portions of the 60 upper surfaces of the spacer rings 6 and 7 is an annular member 8 also preferably of asbestos composition though any other insulating medium would also be acceptable. Abutting the outer edge surfaces of the 65 member 8 and furthermore abutting the complementary portions of the rings 6 and 7 respectively are a pair of upright insulating rings 9 and 10 respectively; these extend upwardly to within a short distance 70 of the inner surface of the receptacle 2. As so positioned, the insulating member 8 should be snugly interposed between the rings 9 and 10 so as to effect an airtight connection therewith. The arrangement is 75 furthermore such that two lateral annular air spaces 11 and 12 respectively and one interjacent air space 13, are provided. It is obvious too that the member 8 and rings 80 9 and 10 together form an annular compartment of rectangular cross section and of correspondingly smaller dimensions. Located in this last mentioned inner compartment is any approved type of resistance coil 14, which coil is operatively connected 85 with terminals each designated by the letter T, as shown in Fig. I. The coil 14 is held in place by being enveloped in the usual manner by any approved packing composition 15, which may consist of equal parts 90 of fire clay, Portland cement and litharge, to have the property of allowing for the expansion of the heated coil. A heat conducting cover 16, composed of mica, is interposed between the upper surfaces of the 95 rings 9 and 10 and the inner surface of the receptacle 2, whereby the inner compartment to which attention has just been directed, is closed and the packing 15 securely held in place.

100 By the provision not only of two insulating walls but of air spaces therebetween which of themselves constitute insulation, I attain the decided advantage of concentrating the radiation of heat in a specific 105 direction, and in fact in this instance in the direction of the mica 16. It is apparent that the radiation of heat in any one of the other three directions, is made practically impossible.

The modification to which Figs. III and IV have reference, is especially adapted for cylinder printing presses, and resides in having the shape of the element straight 5 instead of circular, and in the utilization of a resistance coil extending the full length in one direction and returning. Brackets B are represented to indicate the adopted mode of attachment.

10 My invention being described with sufficient thoroughness, what I desire to secure by Letters Patent and therefore claim specifically, is:

1. An electrical element comprising a pair 15 of receptacles adapted to have telescopic connection with each other, an insulating lining for the inner of said receptacles, an insulating construction establishing air spaces in conjunction with said lining, a 20 heat conducting member forming together with such construction a closed inner compartment, and an electrical resistance medium disposed in said compartment, the latter being spaced from the inner of said 25 receptacles and adjacent the outer of said receptacles for the purpose specified.

2. An electrical element comprising a pair 30 of members of U-shaped cross section adapted to have telescopic connection with each other, a lining completely covering the interior surface of the inner of said members, an insulating U-shaped structure of

smaller dimension within the inner of said members, means for supporting such structure with its closed interjacent surface 35 spaced from said inner member and its open side adjacent a portion of the outer of said members, and an electrical resistance medium placed within said structure so as to be nearer such portion of said outer 40 member than said closed interjacent surface of said inner member.

3. An electrical element comprising a pair of members of U-shaped cross section adapted to have telescopic connection with 45 each other, a lining completely covering the interior surface of the inner of said members, a U-shaped structure within the inner of said members, spacer means supporting said structure whereby to form air spaces 50 adjacent different portions of said lining, an electrical resistance medium set within said structure and a thin heat conducting cover for said structure and abutting a portion of the outer surface of said members 55 whereby to concentrate the radiation of heat therethrough.

Signed by me, this 23rd day of March, 1914.

FRANK J. COOK.
